UNITED STATES PATENT OFFICE.

GEORGE L. JORDAN, OF MINDEN, NEBRASKA.

SAFETY-RAZOR-BLADE HOLDER.

1,205,641.

Specification of Letters Patent. Patented Nov. 21, 1916.

Application filed May 10, 1916. Serial No. 96,631.

To all whom it may concern:

Be it known that I, GEORGE L. JORDAN, a citizen of the United States, residing at Minden, in the county of Kearney, State of 5 Nebraska, have invented certain new and useful Improvements in Safety-Razor-Blade Holders; and I do hereby declare the following to be a full, clear, and exact description of the invention, such as will enable 10 others skilled in the art to which it appertains to make and use the same.

This invention relates to holders for use in sharpening safety razor blades, the object 15 of the invention being to provide an article of manufacture that because of its structure may be made with economy of labor and material, and which will be efficient in its operation.

A further object of the invention is to provide a device of this character which is 20 capable of being readily operated to hold or release the razor blade, which firmly holds the blade to the holder, and which is so constructed as to accommodate blades of various 25 sizes, shapes and constructions.

With these objects in view, together with others which will appear as the description proceeds, the invention resides in the novel combination and arrangement of parts, all 30 as will be described more fully hereinafter, illustrated in the drawings and particularly pointed out in the claim.

The invention will be best understood by reference to the accompanying drawings, 35 wherein:

Figure 1, is a perspective view of a blade holder embodying my invention, and Fig. 2, is a transverse sectional view taken through the blade and holder inclosing the same, and 40 illustrating the manner in which the holder is operated.

In the preferred embodiment of the invention, 3 indicates generally the holder, the same being formed of a single length of 45 relatively heavy spring wire bent intermediate its ends as at 4, the extremities of the wire strand forming blade engaging arms 5. The parts of the wire strand adjacent the intermediate portion are spaced apart, the 50 said portions forming together a handle portion 6, and the arms are then bent or converged and twisted upon each other at 7. Beyond the twisted portion, the arms are straight and lie in close relation to each 55 other. The extremities of the holder arms

are twisted together as at 8, and the blade to be sharpened is adapted to be inserted between the straight portions of the arms and firmly held therein. The twisted arrangement of the arms is such that a blade engaged between the same lies in the same plane with the handle portion 6 of the holder, and rings or sliding sleeves 9 inclose the straight portions of the arms to firmly clamp the latter together upon the razor 60 blade. After a blade has been inserted between the arms, and the rings 9 moved upon the latter to the end of the blade, the pressure created upon the arms by the rings will firmly hold the blade between the same. 65 Reverse movement of the rings will relieve the pressure and the blade may be readily withdrawn. The wire constituting the arms of the device is of such diameter or thickness that when resting upon a hone or strap and 70 inclined to such degree that the blade protruding therefrom rests adjacent its cutting edge upon the hone or strop, at such inclination that rubbing movement of the blade so positioned upon the abrasive surface will 75 properly bevel the cutting edge of the blade. The resiliency of the material of which the holder is formed yieldably supports the blade upon the strop or hone, permitting of the blade properly resting upon the abrasive 80 surface to conform to irregularities thereon. The resiliency of the holder also properly points the cutting edge of the blade held thereby, as, when the holder is lifted from the abrasive surface at the termination of a 85 sharpening stroke, the holder, in springing to normal position, delivers a slight twisting movement to the blade, whereby a wire or uneven rough cutting edge upon the blade is obviated. 90

The device is adapted particularly for use in connection with single edged razor blades, but it is apparent that the double edged blades may with equal facility be accommodated in and sharpened by the improved holder. 100

While I have herein shown and described a particular or preferred embodiment of the invention, I wish it to be understood that I need not confine myself to all the precise 105 details of construction herein set forth by way of illustration as modification and variation may be made without departing from the spirit of the invention or exceeding the scope of the claim appended hereto. 110

What is claimed is:—

As an article of manufacture, a sharpening holder for safety razor blades consisting of a spring wire bent upon itself, the portions of the wire adjacent the bend being spaced apart to constitute a handle, and the end portions lying in close relation, the closely lying portions of the wire being twisted together at their end portions only,

and wire rings upon said closely related portions in contact with both of them.

In testimony whereof, I affix my signature, in the presence of two witnesses.

GEORGE L. JORDAN.
